UNITED STATES PATENT OFFICE

BERT O. TILDEN, OF TRENTON, NEW JERSEY, ASSIGNOR TO B. O. T. MFG. COMPANY,
OF TRENTON, NEW JERSEY, A CORPORATION OF NEW JERSEY

DESIGN FOR A WATER-CLOSET COMBINATION

Application filed July 7, 1930. Serial No. 36,275. Term of patent 14 years.

To all whom it may concern:

Be it known that I, BERT O. TILDEN, a citizen of the United States, residing at Trenton, in the county of Mercer and State of New Jersey, have invented a new, original, and ornamental Design for Water-Closet Combination, of which the following is a specification, reference being had to the accompanying drawing, forming a part thereof.

Figure 1 is a perspective view of the water closet combination showing my new design; Fig. 2 is a top plan; Fig. 3 is a side elevation, and Fig. 4 is a front elevation.

I claim:

The ornamental design for a water closet combination, as shown.

BERT O. TILDEN.
